MINE AND MILL SUPPLY CO., OF PITTSBURGH, PENNSYLVANIA, A CORPORATION OF
PENNSYLVANIA.

CAR-STOP.

1,289,886.

Specification of Letters Patent. Patented Dec. 31, 1918.

Application filed November 7, 1918. Serial No. 261,480.

To all whom it may concern:

Be it known that I, RICHARD B. OSBOURNE, a citizen of the United States, residing at Ingram borough, in the county of Allegheny and State of Pennsylvania, have invented certain new and useful Improvements in Car-Stops, of which the following is a specification, reference being had therein to the accompanying drawing.

10 This invention has relation to car stops and has for its object the provision of novel mechanism for operating the horns or stops of the same.

In coal mining, quarrying, excavating and other industries loaded cars of coal, stone, clay, etc., are made up into "trips" or trains and hauled to some point to be weighed, dumped, hoisted or subjected to some other operation which requires them to pass a given point one at a time. These cars usually stand on a grade which will permit them to pass this point by gravity. To control the trips so that they will pass the given point only as desired, a movable stop or check is placed in the track on which the cars run which allows only the required number of cars to pass it accordingly as the operator desires and determines.

Heretofore the horns or stops in mechanism of this character usually have been operated by means of a hand lever, but, as with a trip of loaded cars standing against them it was difficult to move the horns or stops, their operation by means of a hand lever involved severe physical labor.

In the present invention the horns or stops are operated by the weight of a moving car acting through a track treadle arranged in the line of track so as to be depressed by the wheels of the car and certain mechanism connected with this treadle and the horns or stops and operated by the movement of the treadle whereby, as the horns or stops are operated by the treadle, a strong spring, connected with the said connecting mechanism, is put under tension and the horns or stops locked in the position to which they have been brought by the movement of the treadle.

50 Provision is made for unlocking the horn or stop operating mechanism and opening the horns or stops by the pull of the said

spring, comprising a foot treadle and a tripper, the latter being arranged to bear against and move a pair of toggle arms or levers which constitute the locking means, and thus pass the next car through to the point where it is to be weighed, dumped, hoisted or otherwise manipulated.

In the accompanying drawing which illustrates the invention;

Figure 1 is a plan view of a car stop structure provided with my improvements, a portion of the main platform being broken away to show the mechanism beneath.

Fig. 2, is a side elevation of the same.

Fig. 3, is a vertical sectional view on a larger scale, on the line $x-x$ of Fig. 1.

Fig. 4 is a side elevation of a modified form of my improvement, on the same scale as Fig. 3.

Fig. 5 is a plan view of the construction shown in Fig. 4.

Figs. 6 and 7 are plan and side views respectively and on a still larger scale of parts of the locking mechanism employed in the several forms of my improvement.

Figs. 8 and 9 are plan and side views respectively of another part of the locking mechanism, on the same scale as Figs. 6 and 7.

The apparatus constituting my improvement is designed to be arranged in a line of track leading from a source of supply such as a mine, quarry or the like and is mounted on the ground or at any required elevation on suitable supports in the usual manner.

The horn or stop mechanism is mounted on a platform or base plate 1, which is in turn mounted on L shaped beams, 2, 3, and at a suitable distance beyond the platform 1, there is a second platform 4, both platforms 1, and 4, being supported on I beams 5 and 6.

The platform 1, carries two tracks designated respectively 7 and 8, each of these tracks being composed of two L-shaped beams securely bolted together and to the platform 1, the tracks so formed being of approximately Z shape as shown in cross section in Fig. 3.

The platform 4 is provided with two tracks 9 and 10, aligned with the tracks 7

and 8, of platform 1, and inclined track sections 11 and 12, connect the track sections 7 and 8, with the track sections 9 and 10.

Upon the outer side of each of the track sections 7 and 8 of platform 1, are arranged two longitudinally movable and oscillatory bolts 11 and 12, these bolts being mounted in bearing blocks 15, and provided with buffer springs 16.

10 The bolts 11, 12, carry horns or stops designated respectively 17, 18, the horns or stops being fast on the bolts and the latter being so connected to the hereinafter described operating mechanism that the horns 15 or stops can be turned to a vertical or closed position, so as to stop a car on the tracks 7, 8, or to an outwardly inclined or open position, so as to allow a car to pass.

Below the platform 1, is arranged a cruciform lever having four arms, 21, 22, 23, and 24, this lever being fulcrumed on a vertical bolt 25, and mounted on a bracket 26 which is attached to the lower surface of platform 1.

25 A rod 27, is pivotally attached to the arm 21, and extends to and beneath platform 4, and is there pivotally attached to an arm 28, depending from a track treadle 29 that is arranged in a cut out portion 30, of the track 9, and mounted on arms 31, 31, that are pivotally attached at their upper ends to the track treadle 29 and similarly attached at their lower ends to brackets 32, 32, depending from the platform 4.

30 35 A strong spring 33, is attached at one end to the arm 23 of the cruciform lever and at the other end is attached to the frame of platform 1, this spring being put under tension by the depression of the track treadle 40 and consequent rotary movement of the cruciform lever.

45 A rod 34, is pivotally attached at one end to a curved arm 35, that depends from bolt 11, and at its other end is pivotally attached to the arm 24 of the cruciform lever and a similar rod 36, is pivotally attached at one end to a curved arm 37 that depends from bolt 12, and at its other end is pivotally attached to the arm 22, of the cruciform lever.

50 55 A link 38, composed of two parallel bars, is pivotally attached to the arm 24, of the cruciform lever and at its other end is pivotally attached to a swinging link-bolt 39 that projects through a swivel block 40 (see Figs. 8 and 9) that is swiveled in a bracket 41 depending from platform 1.

60 Lock nuts 40, 40', provide for the adjustment of the link-bolt 39, in the swivel block 40.

65 The link 38, and link bolt 39 serve to form a toggle lever lock for the cruciform lever, as, when the link and link bolt assume a position slightly beyond exact alinement, (dotted line position, Fig. 5), movement of

the cruciform lever by the pull of spring 33 is prevented, further movement to the right beyond the dotted line position Fig. 5, being stopped by contact of link bolt 39 with a tripper 41.

70 The function of the tripper 41, is to throw the toggle-lever lock off the substantially dead center position shown in dotted lines in Fig. 5, to a position where the pull of spring 33, can bring it to the full line position as shown in Figs. 1 and 5.

75 In order to assist the link 38 and link bolt 39 to assume the dotted line or locked position, a link 42 is pivotally attached to the link bolt 39 at about the middle of the latter and the link 42, is forked at its outer end and embraces an angularly disposed and upwardly extending arm 43, carried by a collar 44, that is slidably mounted and keyed upon a rock shaft 45, that is journaled in hangers 46, 46, depending from platform 1.

80 The outer end of rock shaft 45, carries a rigid arm 47, upon which is adjustably mounted a weight 48 that is held in adjusted position by a set screw 49.

85 The tripper 41, is pivotally mounted between hangers 50, 50, and its lower arm is connected by a crank rod 51, with a crank arm 52, carried on the inner end of a rock shaft 53, that is mounted in hangers 54, 95 depending from the platform 1.

90 The outer end of the rock shaft 53, carries a crank arm 55, that is connected to rod 56, extending under and to near the extreme end of platform 4, where it is connected to a bell-crank lever 57, mounted on a hanger 58. The horizontal arm of the bell crank lever 57, is pivotally attached to the lower end of a vertically movable foot treadle 59 and by the depression of this foot treadle, through the operation of the above described connecting parts, the tripper 41, is operated to move and unlock the toggle-joint lock comprising link 38 and link-bolt 39, by moving them from the dotted line position shown in Fig. 5, to an equivalent position at the opposite side of a line intersecting the pivotal points of the toggle joint, whereupon the pull of the spring 33, exerted through the cruciform lever, will throw the link 38 and link bolt 39 into the full line position shown in Figs. 1 and 5.

100 105 110 The description of the construction, arrangement and operation of parts hereinbefore described is equally applicable to all the figures of the drawing and consequently the same numerals have been employed to designate corresponding parts in the several figures, the only difference between the construction shown in Figs. 1, 2 and 3, and that shown in Figs. 4 and 5, being that in the construction shown in Figs. 1, 2 and 3, two cruciform levers and two pairs of horns or stops, are employed, while in the construction shown in Figs. 4 and 5, but one 115 120 125 130

cruciform lever and one pair of horns or stops are employed, the locking means and other appurtenant parts being identically the same in both constructions. For this reason it has been unnecessary to show the platform 4, and the parts carried thereby in Figs. 4 and 5 and these parts have accordingly been omitted.

Referring now particularly to Figs. 1, 2 and 3, it will be observed that a second cruciform lever is arranged below platform 1, this lever having four arms, 21', 22', 23', and 24', the arm 21', being connected to the arm 21 of the first described cruciform lever by connecting rods 19, 19', which are adjustably connected together by a turnbuckle 20, and this second cruciform is pivotally mounted at 25', on a bracket 26', carried by platform 1.

20 The arm 21', of the second cruciform lever is pivotally connected to a rod 34' that is pivotally attached to a curved arm 35', that depends from the bolt 11', that carries the horn or stop 17', and the arm 24' of 25 this cruciform lever is pivotally connected to a rod 36' that is attached at its outer end to a curved arm 37', that depends from the bolt 12' which carries the horn or stop 18'.

It will be observed that the connection 30 between the two cruciform levers and their respective horns or stops is such that when the horns or stops 17 and 18 are in an outwardly extending or open position, the horns or stops 17', and 18', will be in a vertical 35 or closed position and vice versa.

A strong spiral spring 33', is attached at one end to the arm 23', and at the other end to the platform frame, and serves to draw the horns or stops 17', 18', into vertical or 40 closed position when the toggle joint locking mechanism connected with arm 24 of the first described cruciform lever is released or unlocked by the tripper 41.

Operation.

45 Referring first to the construction shown in Figs. 1, 2, and 3, wherein two pairs of horns or stops are employed, and assuming that the direction of movement of the car or cars is in the direction indicated by the arrow X, and that the horns 17-18 are opened and the horns 17', 18', are closed and that there is a single car at a position between the two pairs of horns and a trip or plurality of cars held back of the first named car by the horns or stops 17', 18'.

Under the action of gravity the car between the two pairs of horns 17, 18, and 17', 18', will move in the direction indicated by 60 arrow X, and pass onto and over the track treadle 29. As the car passes over the track treadle, depressing it, the horns 17, 18, will be closed and the horns 17', 18', will be opened, allowing the trip to advance to the 65 horns or stops, 17, 18. During this opera-

tion the springs 33, 33' are brought under tension and the horns or stops are locked by the toggle-lever locking mechanism.

When the operator wants the next car to proceed he depresses the foot treadle 59, and 70 the motion communicated to the tripper 41, by bell crank lever 57, and rod 56, rock shaft 53, and rod 51, causes the tripper to press against the link bolt 39, and throw the toggle lock out of locked position and 75 allow the springs 33, 33' to open the front horns 17, 18, and thus allow another car to pass on, and close the horns or stops 17', 18', thus holding back the trip or train until it is desired to send another car forward in the 80 direction indicated by arrow X.

In the construction illustrated in Figs. 4 and 5, where but one pair of horns or stops is employed, the operation is as follows.

Assuming that a car has passed the horns 85 or stops, 17, 18, moving in the direction indicated by the arrow X, the car will run onto the track treadle (it being understood that the apparatus shown in Figs. 4 and 5, is provided with the same operating appurtenances as are shown in Figs. 1, 2, and 3,) and will depress the track treadle and will close the horns 17, 18, in which position they will be locked by the toggle-joint lock 90 mechanism. The trip behind the car which 95 has operated the track treadle, advancing by gravity, will be caught and held by the closed horns or stops which will have assumed the closed or vertical position before the trip reaches them. To pass the next car 100 along, the operator depresses the foot treadle 59, (see Figs. 1 and 2,) tripping the toggle joint lock, 58, 59, thus permitting spring 33, which was brought under tension by the depression of the track treadle, to open the 105 horns and allow the car to pass, and this operation being repeated as long as there are any cars in the trip or train.

I claim:

1. In apparatus of the character described, 110 the combination of a platform, tracks carried by the platform, horns or stops arranged adjacent to the platform tracks and adapted to be opened and closed, a track treadle arranged in a continuation of said platform tracks, mechanism connecting said horns or stops and said track treadle and adapted to move the horns or stops upon depression of the said track treadle, a spring connected to the horn or stop operating mechanism and adapted to be put under tension by the depression of the track treadle, a toggle joint locking device connected to the horn or stop moving mechanism and adapted to lock the same against movement 115 by said spring, a tripper arranged and adapted to unlock said locking device and allow said spring to move the horns or stops, and a treadle connected to and adapted to operate said tripper. 120

125

130

2. In apparatus of the character described, the combination of a car track, movable horns or stops adjacent said track, a pivoted cruciform lever adapted to move said horns or stops, a track treadle arranged to operate said lever, a spring connected to the said lever and adapted to be put under tension by the movement thereof, a toggle-joint locking device connected to said lever, a tripper 10 adapted to unlock said locking device and a foot treadle operably connected to said tripper.

3. In apparatus of the character described, the combination of a track, movable horns or stops on said track, mechanism including a track treadle for moving the horns or stops, a spring connected to the horn or stop moving mechanism, and adapted to be put under tension by the movement of the track 20 treadle, means for locking the horn or stop moving mechanism and a treadle and tripper adapted to unlock the said locking means.

4. In apparatus of the character described, the combination with a track and movable horns or stops arranged in the line of the track, of a pivoted lever adapted to move the horns or stops, means for positively moving said lever in one direction and a spring adapted to move said lever in the opposite 30 direction, means for locking said lever

against movement by the spring, a tripper adapted to throw said locking means out of locking position and means for operating said tripper.

5. In apparatus of the character described, the combination with a car track, movable horns or stops arranged in the line of the track and a pivoted lever having a plurality of arms, said lever being connected with and adapted to move said horns or stops, of a track treadle connected with and adapted to move said lever, a spring connected with the said lever and adapted to be put under tension by the movement imparted to the lever by the track treadle, a locking device 45 for locking said lever, a foot treadle and a tripper connected thereto for unlocking said locking device, a second pivoted lever adjustably connected to the first named lever, movable horns or stops connected to the second lever and adapted to move simultaneously with but in opposite direction to the first named horns or stops. 50

In testimony whereof I have affixed my signature in presence of two witnesses.

RICHARD B. OSBOURNE.
